United States Patent Office.

NELSON S. SNEDEKER, OF PHILADELPHIA, PENNSYLVANIA.

Letters Patent No. 61,109, dated January 8, 1867.

IMPROVEMENT IN LUBRICATING JOURNALS.

The Schedule referred to in these Letters Patent and making part of the same.

TO ALL WHOM IT MAY CONCERN:

Be it known that I, NELSON S. SNEDEKER, of the city of Philadelphia, State of Pennsylvania, have invented a new and useful Swab for Lubricating Open Journals; and I do hereby declare that the following is a full and exact description of the same, reference being had to the annexed drawings, in which—

Figures 1 and 2 are perspective views of the mat or nappy fabric (in an unfinished state,) used by me in the manufacture of my improved swab, these figures being intended principally to show the wire warp and the attachment thereto of the loops or tufts that form the nappy face of the mat.

Figure 3 is a perspective view of the complete swab.

Figure 4 is a vertical section of the journal and bearing of a lower roll, such as is used in rolling-mills, showing one method of applying the swab.

Figure 5 shows another method of applying the swab.

Figure 6 is a similar section of the journal of an upper roll, with a rider and a carrier, without side bearings, showing another mode of applying the swab.

Figure 7 represents a similar section of a journal with side bearings, showing another mode of applying the swab.

In figs. 1 and 2 the blue lines *a* represent the woollen woof, the red lines *b* the warp or chain consisting of brass wire or other suitable wire. In fig. 2, *c* are loops or tufts of woollen yarn introduced during weaving in the usual manner, so as to form the nappy face of the fabric. This fabric is woven on an ordinary loom. In fig. 3, *d* represents a plate of sheet iron, tin, copper, or other suitable metal forming the back of the swab, the nappy fabric above described being fastened to this by rivets, as shown, or in any other substantial manner, and the back being curved so that when applied to a journal the swab shall conform to the surface thereof. *e*, fig. 3, is a hinge by means of which the swab may be fastened to the bearing of the journal, as shown in fig. 4. When the swab is intended for the journals of rolling-mill rolls the back is made to extend a few inches, say from two to six, according to circumstances, over the nappy fabric on one side of the swabs, the extension forming an economical means in place of the hinge, as shown in fig. 3, for securing the swab in its proper place on the journal. Oil is applied to the face of the swab as often as occasion may require.

Having thus described my invention, what I claim, and desire to secure by Letters Patent, as a new article of manufacture, is—

A lubricator composed of woollen plush interwoven with a wire warp and united to a metallic back with rivets or their equivalents.

N. S. SNEDEKER.
